UNITED STATES PATENT OFFICE

JOHN T. SCHAAFF, OF WASHINGTON, DISTRICT OF COLUMBIA, ASSIGNOR TO THE TABULATING MACHINE COMPANY, OF ENDICOTT, NEW YORK, A CORPORATION OF NEW JERSEY

RIBBON MECHANISM

Original application filed July 6, 1927, Serial No. 203,765. Divided and this application filed June 28, 1928. Serial No. 288,386.

This case relates to ribbon feeding and reversing mechanism and is a division of my application Serial No. 203,765, filed July 6, 1927.

5 The object of this invention is to provide improved means for feeding and reversing the feed of an inking ribbon.

Another object is to impart a lateral shifting movement to the ribbon carrying frame 10 itself to distribute the wear on the ribbon evenly.

Various other objects and advantages of my invention will be obvious from the following particular description of one form of 15 mechanism embodying the invention or from an inspection of the accompanying drawings; and the invention also constitutes certain new and novel features of construction and combination of parts hereinafter set 20 forth and claimed.

In the drawings:

Fig. 1 is a side view of the ribbon mechanism;

Fig. 2 is an end view of one of the ribbon 25 spool mechanisms;

Fig. 3 is a section on line 3—3 of Fig. 2;

Fig. 4 is a top view of one of the spools when the ribbon is completely unreeled therefrom;

30 Fig. 5 is a side view of the machine in which the ribbon mechanism is employed;

Fig. 6 is a detail of the ribbon frame shifting means.

While the application above referred to 35 concerned a card controlled printing machine, the ribbon mechanism thereof is generally applicable to any other type of printing machine where an inking ribbon is required, as will be clear from the following 40 description.

The ribbon mechanism detailed in the 45 drawings consists of the ribbon spools 116 with ratchet teeth 117 cut in both rims of each spool. Associated with each spool is a feed pawl 118 pivoted to a sliding member 119 and held by a spring 120 toward the ratchet teeth. When the feed pawls move up, one of them engages the ratchet teeth to rotate the associated spool and wind the ribbon thereon. To impart this upward move-

ment to the feed pawls, members 119 to which they are attached are raised once every cycle of the printing machine by oscillating bars 121 which engage the lower sides of pins 122 attached to extensions 123 of members 119. 55 There is one of said bars 121 fixed to each end of a shaft 124 which is oscillated by linkage 125 from shaft 57 (Fig. 5) of the printing mechanism. As shaft 124 is oscillated, the bars 121 in their upward movement engage the pins 122 to lift the feed pawls. But only one of the feed pawls is engaged with the cooperating ratchet teeth, the other feed pawl being held out of engagement with the ratchet teeth by contact of the side of the 60 adjacent bar 121 with the face of said latter pawl, as seen in Fig. 1 and as will be further described hereinafter. Thus while both pawls are actuated, only one ribbon spool is positively rotated to wind the ribbon thereon. In 65 their downward movement, bars 121 permit the pins 122 and the feed pawls to drop by gravity. When the ribbon is entirely wound on one spool, shifting mechanism comes into action to cause positive rotation of this spool 70 to cease and positive rotation of the other spool to begin. In Fig. 1, the position of the parts of the ribbon mechanism during shifting is shown. The left hand spool has been positively rotated to wind the ribbon indicated by E, thereon, while the right hand spool has been rotated by the pull of the ribbon 75 and is shown with the ribbon entirely unreeled therefrom. Attached to the end of the ribbon is a bail 126 (Figs. 3 and 4) pivoted to the spool sides at 127 and having a projection 128. As the end of the ribbon on the right hand spool (Fig. 1) attempts to leave the spool, it pulls on the bail causing it to pivot upward, and as a result bail projection 128 contacts the inclined under side 80 of an arm 129 which has an extension 130. 85 The passing engagement of bail projection 128 with the arm 129 rocks the latter and its extension 130 counterclockwise on a pivot 131, positioning the end of extension 130 over the bar 121. When the latter rocks upwardly it engages the end of extension 130 now positioned over it and raises the extension 90 and arm 129, the movement of the latter tak-

ing place about a pivot 132 fixed in plate 133 rigid with the frame. The pivot 132 has journalled thereon one end of a pawl 134, the other end of which is journalled on pivot 131. The pawl 134 is thereby raised and the nose 135 thereof is lifted out of engagement with a lug 136 on a sliding plate 137 permitting a spring 138 attached thereto to move it to the right, (Fig. 1). As the plate 137 moves to the right, it engages and moves the right hand feed bar 121 with it and out of contact with the face of the feed pawl 118 which is then moved by the spring 120 into engagement with the ratchet teeth in position to rotate the spool and wind the ribbon thereon. In moving to the right, bar 121 moves the shaft 124 with it. Attached to the other end of the shaft 124 is the left hand bar 121 of the other spool 116 and as the shaft moves to the right it also moves the left hand bar 121 to the right. In this movement, the left hand bar 121 engages the face of the associated feed pawl 118 and holds it disengaged from the cooperating ratchet teeth 117, rendering the pawl inoperative to rotate the spool. The feed of the ribbon is thus completely shifted. To hold shaft 124 in position until shifted an impositive detent 139 on shaft 124 moves over the end of a latching arm 140 pivoted to the ribbon frame and yieldingly held in its upper position by a spring 141. The spring permits the detent 139 to pass over the latch and engage its other side by which it is held locked in position. As soon as the feed of the ribbon is shifted, plate 137 is moved back to its inactive position to the left. In order to release the pawl 134 and permit it to engage and hold the plate inactive the plate must be moved to the left against the force of spring 138. For this purpose, a bell crank 143 is attached to the plate at one end 144 and in its inactive position, the plate keeps the other end 145 of the bell crank out of the path of cam 146 on the outer end of the main shaft 10 (Fig. 5) projecting from the sides of the machine frame. When the shifting mechanism causes the plate to move to the right, it oscillates the end 145 of the bell crank into the path of the cam 146 which when it comes into contact therewith, during the same or the succeeding cycle, moves the bell crank 144 and the plate connected thereto to the left, permitting the pawl 134 to drop and hold the plate in this position while cam 146 has no further effect on the bell crank the end 145 thereof being out of its path. Detent 147 prevents retrograde movement of the spool by engagement with one set of ratchet teeth on the spool. When bar 121 moves to disengage the feed pawl 118 from the ratchet teeth of the spool, in the manner heretofore described, it simultaneously acts against the face of the detent 147 to similarly disengage the detent from its cooperating ratchet teeth,

thus leaving the spool free to be rotated by the pull of the ribbon being wound on the other spool.

A spring pressed pin 171 bears against the end of the spool shaft and urges a friction knob 175 towards the surface of frame plate 133. A leather washer is placed between the knob and the plate, the friction of the washer preventing overthrow of the spool from which the ribbon is being unwound.

Fixed rods 172 are provided to guide the ribbon in its travel.

For the purpose of evenly distributing the wear on the ribbon, spool supporting frame F is given a periodic transverse movement by 80 means of an eccentric roller 148 which engages the walls of a recess 149 therein. The roller is given a step by step rotation by means of a ratchet wheel 150 fixed to the shaft of the roller, which ratchet wheel is actuated by a pawl 151 receiving motion from link 113 of the card stacking mechanism. A holding pawl 152 is provided to prevent reverse movement of the ratchet wheel.

While I have shown and described and 90 pointed out the fundamental novel features of the invention as applied to a single modification it will be understood that various omissions and substitutions and changes in the form and details of the device illustrated 95 and in its operation may be made by those skilled in the art without departing from the spirit of the invention. I intend to be limited therefore only as indicated by the scope of the following claims.

I claim:

1. In a ribbon mechanism, a spool, a pawl for rotating the spool, driving means for moving the pawl to rotate the spool, a device for actuating said means to release the pawl from the spool whereby the pawl is ineffective to rotate the spool, a member for preventing operation of said device to actuate said means, and an element operated directly by said driving means for releasing said member and permitting said device to actuate the driving means for releasing the pawl.

2. In a ribbon mechanism provided with a pair of spools and a pawl coacting with each spool to drive the latter; a pair of driving elements, one for actuating each pawl, each element being adapted to release the corresponding pawl from its spool, means for actuating said elements to cause one of the latter to release the corresponding pawl from the spool, means for restraining action of the first-named means, and a device actuated by one of said elements for releasing the restraining means from the first-named means and permitting the latter to actuate the other of said elements to release its corresponding pawl from the spool.

3. In a ribbon reversing mechanism, a spool, a pawl for rotating the spool, a member for holding the pawl disengaged from the

- spool, a device for actuating said member to release the pawl for engagement with the spool, an element controlled by the ribbon on the spool for preventing movement of said device for actuating said member, said element being releasable from the device to permit movement of the device to actuate the member and thereby release the pawl for rotating the spool, and means for automatically returning said device to its initial position after it has moved to actuate said member, said device remaining in said initial position while said pawl is engaging and rotating said spool.
- 5 4. In a ribbon mechanism, a spool, a pawl for rotating the spool, a device for releasing the pawl to permit it to engage and rotate the spool, means for actuating said device, a member for preventing actuation of the device by said means, and a holding element controlled by the ribbon on the spool for disengaging said member from said device whereby it may be actuated by said means to release the pawl for rotating the spool.
- 10 5. A mechanism as set forth in claim 4, said means comprising a spring normally urging said device in a direction to release the pawl.
6. A mechanism as set forth in claim 4, and means for automatically returning the device to initial position while the pawl remains in engagement with the spool.
- 15 7. A mechanism such as set forth in claim 4 including a continuously moving member, and a link actuated by the device upon the release of the latter into cooperation with said member whereby the member is adapted to actuate said link for returning the device to initial position.
8. A mechanism such as set forth in claim 40 4, a cam member, and a link for cooperating with said member, said link being connected to said device and normally held by said device out of contact with said cam, and movable by said device when the latter is released into contact with the cam whereby the cam and link return the device to initial position.
9. A mechanism as described in claim 4, said device comprising a plate provided with 45 a shoulder and said member comprising a dog engaging said shoulder to prevent movement of the device.
10. A mechanism as described in claim 4, and a shaft including a driving element engageable with the pawl upon oscillation of the shaft for actuating the pawl to rotate the spool, said holding element being actuated by the driving element to cause said member to disengage the device whereby the pawl is 50 moved into engagement with the spool.
- In testimony whereof I hereto affix my signature.

JOHN T. SCHAAFF.
